RADIO RECEIVING STATION.

Application filed June 25, 1924. Serial No. 722,361.

The present invention relates to subscribers' station circuits and apparatus for combined radio and wired radio receiving systems in which current is supplied to the subscribers for operation of their radio sets over a distributing wire such as a telephone line, electric light line or the like. It has for its object to render the supply of energy to the subscribers' radio receiving circuits substantially constant regardless of variations of potential in the supply line such as would be caused by the connection or disconnection of a telephone or other current consuming device across the line. The present invention is intended for use particularly with a combined telephone and radio telephone system in which the telephone system is of the usual centralized battery or common battery type. Where such centralized battery system is used in the combination, a constant potential is maintained on the lines, so that when the telephones are not in use, the radio telephones can be adjusted so as to function properly on the telephone circuit using the metallic circuit only, without substation grounds. However, when the telephone transmitter which is of low resistance is bridged across the line a drop of potential occurs at the subscriber's station due to the series resistance of the line which must be compensated for in order to maintain proper function of the subscriber's radio telephone apparatus especially with respect to the filament current and plate potential. I attain my object by providing at the subscriber's radio telephone station a source of current of sufficient potential and current supplying capacity to compensate for the drop in potential due to the bridging of the telephone transmitter across the line and restrict the use of current from said local source for this purpose by providing means permitting current to flow from the line past the local source to the subscriber's radio telephone or from the line to the local source, but preventing the flow of current from the local source to the line, which enables the local source to supply sufficient energy to compensate for the potential drop without the necessity of having to abnormally increase the flow of current through the current consuming device such as the telephone receiver in order to satisfy the equation of Ohm's law, $E = RC$.

A preferred form of my invention is illustrated in the accompanying drawings, in which:

Fig. 1 is a simplified or schematic diagram of the invention in its simplest form.

Fig. 2 is a diagram showing the invention applied to a combined radio telephone and telephone exchange system using common battery supply.

Referring to the drawings in detail and first to Fig. 1, 1 is a radio telephone receiving set having an audion tube or similar electron discharge device 2. 3 and 4 represent a pair of line wires such as those of the telephone line supplied with current from a constant potential source such as the battery B. The line wire 4 extends directly to the circuits of the receiving set 1 while the line wire 3 is extended through an electrolytic rectifier 5 to the plus bus wire 6 of the radio telephone set 1. A telephone set T is connected across the line 3-4 with the usual switchhook 7 for opening and closing its transmitter circuit across the line, which circuit consists of the usual induction coil winding 8, switchhook contacts 9 and 7, and transmitter 10. The horizontal distance between the vertical dotted lines separating the battery B from the telephone set T represents the indefinite or variable distance between the battery B located at the telephone central station and the telephone and other apparatus located at the subscriber's station. The plate 11 of the discharge device 2 is directly connected with the conductor 6 while the filament 12 is connected through resistance 13 and choke coil 14 to the plus conductor 6, at its plus terminal, and has its minus terminal connected directly to the minus line conductor 4. Bridged across the conductors 4 and 6 is a local source of current B², preferably in the form of a storage battery of a potential substantially equal to or less than that of the primary source B. As the battery of the usual common battery telephone exchange system is about 25 volts, this voltage is chosen for the battery B in the present instance so that the voltage of the battery B² will also be substantially equal to or slightly less than 25 volts and the filament resistance 13 is adjusted to supply the proper operating current to the filament 12, the full voltage between the conductors 6 and 4 being

supplied to the plate-filament circuit. The rectifier 5 is connected in the circuit 3-6 to permit the flow of current thereover only in a direction as indicated by the arrow 15.

5 In operation, assuming the telephone T to be disconnected from the line as shown, the full voltage of the primary battery B will be maintained on the conductors 6-4, by virtue of the direct connection of conductor 4 with the minus side of battery B and connection of the conductor 6 through rectifier 5 and line wire 3 with the plus terminal of the battery B, and as the rectifier 5 permits current to pass in the direction of the arrow 15 the filament 12 will be supplied by current from the main battery B over line wire 3, rectifier 5, conductor 6, choke coil 14, resistance 13, filament 12, and back over line wire 4 to battery B. It is found in practice that under such conditions very little or no current is supplied by the battery B² and that the plate voltage, or voltage between the conductors 6-4, is substantially the full line voltage. The subscriber's radio telephone circuit 1 is thus maintained properly energized for reception of radio signals in the receiving device R, which may be the usual telephone headset. When the telephone set T is brought into use by raising the switchhook 7 the circuit and its transmitter 10 is connected across the line wires 3-4, by way of induction coil winding 8 and the switchhook contacts 9-7, and as the resistance of the transmitter is comparatively low, there will be a drop in the line potential due to the flow of current therethrough and through the line and its resistance. Due to the presence of the secondary battery B² the normal difference of potential between the conductors 6-4 will be maintained by said secondary battery from which energy will not be drawn by the transmitter T because of the presence of the rectifier or current valve 5. Energy draft from the battery B² is thus limited to the requirements of the subscriber's radio telephone receiver 1. The term secondary as applied to the battery B² is simply indicative of its relation to the main battery B and it is to be understood that it may take the form of any type of current source such as a primary battery, secondary or storage battery, or dynamo generator. It is preferable to use a storage battery for the battery B², in which case it will receive charging current from the main battery when the switchhook 7 is down and the telephone T is disconnected from the line.

60 Fig. 2 shows a more complete system embodying the invention in which the circuits and apparatus to the right of the dotted lines 17 represent that portion of the system situated at the central office of a common battery telephone exchange system, while

the circuits and apparatus to the left of the dotted lines 17 represent that portion of the system which is situated at a subscriber's station, the portion between the dotted lines representing the usual telephone line circuit connecting to subscriber's station with the telephone exchange. At the telephone central office the subscriber's lines 3-4 terminate in multiple jacks 18 and 19 with which connection is made through the operator's cord circuit 20 having tip and sleeve conductors 21 and 22 for connecting the common battery B to the tip and sleeve multiple conductors 23 and 24, respectively, on the subscriber's line. The operator's cord circuit 20 is also provided with a listening key 25 for connecting the operator's telephone headset 26 with the cord conductors. The line wires 3-4 are connected at the subscriber's station with the subscriber's telephone set T in the usual manner and are also connected with the terminal of a radio telephone jack 27 by which the subscriber's radio telephone set 1 may be connected to a line through radio plug 28. The subscriber's radio telephone set consists of the usual antenna 29 to which the input circuit of the discharge device 2 is coupled by means of the input circuit 30 tuned by the variable condenser 31. It is also provided with the usual telephone headset R included in series with a feed back coil 32 in the plate circuit. Conductors 36 and 34 are the current supply conductors for the radio telephone set and correspond to the conductors 6-4 of Fig. 1, except that instead of being permanently connected to the line through rectifier 5, they are connected to the line in series with the rectifier 5 through radio plug 28, the conductor 34 being directly connected with the sleeve terminal of the radio plug and the conductor 26 connected with the tip terminal through the rectifier 5 and conductor 33. The battery B² is a storage battery of substantially the same voltage as that of the battery B and has its plus terminal connected to the tip conductor 36 and its minus terminal connected to the sleeve conductor 34, so as to be in opposition to the main battery B which is similarly connected to the tip and sleeve conductors of the cord 20. The output or plate circuit of the subscriber's radio telephone set is thus connected across the tip and sleeve, or plus and minus conductors 36 and 34 and the plus and minus terminal of the secondary battery B² through the circuit which may be traced from battery B², from conductor 36, receiver R, feed back coil 32, plate 11, filament 12, and conductor 34 back to battery B². The filament 12 is also connected across the conductors 36 and 34 but in series with an impedance coil 14, and resistance 13.

The rectifier 5 is connected to pass current in the direction of the arrow 15 and to facilitate passage of the voice or telephone currents therethrough its terminals may be bridged by a condenser 35.

- With the radio plug 28 removed from its jack 27, the connections between the subscriber's station and the telephone central station are substantially the same as that of the usual common battery telephone exchange system, the subscriber's line circuit being open when the receiver hook is down as indicated in the drawing. With the radio telephone plug 28 of this jack 27 and the central station common battery B connected to the line through the plug 37 and multiple jack 18, the subscriber's radio set 1 is supplied with current from the main battery B over the following path: Battery B, tip or plus cord conductor 21, plug and jack connection 37-18, line wires 3, jack and plug connection 27-28, conductor 33, rectifier 5, plus conductor 36 through plate and filament circuits of the subscriber's radio telephone set to conductor 34, and thence through plug and jack connection 28-27, line wire 4, jack and plug connection 18-37, tip cord conductor 22 and back to the main battery B. As the voltage of the secondary battery B² is substantially the same or less than that of the main battery very little or no current is supplied by it to the radio telephone set. When the telephone T is brought into use by raising its switchhook 7, the transmitter 10 is connected across the line through conductor 39, induction coil winding 8, contacts 9-7, transmitter 10, and conductor 40. This produces a drop in potential across the line conductors 3-4, which, however, will not draw current from the secondary battery B² due to the current valve 5 which prevents the flow of current from the plus side of this battery back over the conductors 36 and 33 to the line conductor 3. The subscriber's radio telephone set is now supplied with current from the secondary battery B². During non-use of both the radio telephone 1 and the telephone T the secondary battery B² may be charged from the main battery B by opening the switch 38 and leaving the radio telephone set connected to line through the plug and jack connection 28-27. The charging circuit may be traced from the plus terminal of main battery B, over conductor 21, plug and jack connection 37-18, line wire 3, jack and plug connection 27-28, conductor 33, rectifier 5, conductor 36, secondary battery B², conductor 34, plug and jack connection 28-27, line conductor 4, plug and jack connection 18-37, and conductor 22 back to the minus terminal of the main battery B.

By thus preventing the flow of energy from the local battery back into the line, its energy is not only conserved but exces-

sive flow of current through the transmitter 10 is avoided. The use of the rectifier 5 also permits battery B² to be of somewhat lower voltage than the main battery so as to be readily charged thereby and to give very little or no current when the telephone T is disconnected from the line. For example, when the telephone is disconnected from the line current will be supplied to the radio telephone set from the main battery B over the line through the rectifier 5 with but slight drop in potential due to the small amount of current taken by the filament 12 through the line resistance, and if the voltage of the secondary battery B² is substantially equal to the resulting voltage across the conductors 36-34 it will simply be floated on the line and supply no energy thereto. Thus if the battery is designed to give this voltage fully charged it will recharge during use of the radio set whenever it is slightly below charge but always give current to the radio set whenever the telephone transmitter 10 is connected across the line.

While a specific embodiment of the invention is herein shown and described for the purpose of disclosure, it is to be understood that the invention is not limited to such specific embodiment but contemplates all such variations and modifications thereof as fairly fall within the scope of the appended claims. For example, any form of rectifier may be used in place of the electrolytic rectifier shown, and other forms of source of current may be used in place of the battery shown.

Having thus described the invention, what is claimed and desired to be secured by Letters Patent is:

1. In a combined radio receiving and telephone system, a pair of line wires, a central office source of current supply for said line wires, a subscriber's telephone of relatively low resistance connected to said line wires, a subscriber's radio receiving set of relatively high resistance also connected to said line wires, means for supplying current from said central source to either or both of said instruments over the line wires, a local booster storage battery connected across the line wires between said instruments and a current valve connected in one of said lines wires between the telephone and the radio receiving set in a manner to prevent discharge of current from said storage battery to said telephone while permitting the flow of current from said telephone to both the storage battery and the radio receiving set.
2. In a combined radio receiving and telephone system, a pair of line wires, a central office source of current supply for said line wires, a subscriber's telephone of relatively low resistance connected to said line wires, a subscribers radio receiving set of

relatively high resistance also connected to said line wires, a subscriber's local storage battery connected to be charged over the line and to supply current to the subscriber's 5 radio receiving set only and a current valve connected to permit the flow of current from the line to both said storage battery and

subscriber's radio receiving set, but to oppose the discharge of the local battery through the subscriber's telephone. 10

In testimony whereof I hereunto affix my signature.

HARRY F. LÖWENSTEIN.
